UNITED STATES PATENT OFFICE.

GUSTAVE ANTOINE RENAULT, OF PARIS, FRANCE.

CATCH FASTENER WITH LOCKING DEVICE FOR PINS, BROOCHES, AND THE LIKE.

Application filed June 8, 1920. Serial No. 387,333.

To all whom it may concern:

Be it known that I, GUSTAVE ANTOINE RENAULT, a citizen of the French Republic, residing at Paris, Rue Reaumur 37, Seine, 5 in State of France, have invented certain new and useful Improvements in Catch Fasteners with Locking Devices for Pins, Brooches, and the like; and I do hereby declare the following to be a full, clear, and 10 exact description of the invention, such as will enable others skilled in the art to which it appertains to make and use the same.

Many kinds of jewelry articles are used, such as brooches, hat- and tie-pins, etc., 15 which consists of two parts, the first part being the properly called pin, the second part having the shape of a sheath or case, in which the point of the first part is located. After the pin has been put through the tissue, on which the jewel is to be fastened, the 20 first part or pin is usually secured in the second part by means of a transverse slot (cut in the body of the pin) and a small tenon connected with a small flat spring, riveted on the body of the second part.

Such a construction has considerable inconveniences: First, the pin is not securely fastened at all; secondly, it tears the tissue on which the pin is fastened, this being done, 30 either by the sharp edges of the aforesaid slot, or by the said tenon, which catches the tissue, when coming into the slot.

The object of the invention herein described is an improved device avoiding the 35 aforesaid inconveniences.

Figure 1 is a longitudinal section through the device attached to a hat pin, and

Figure 2 is a section taken on the line $x-x$ in Figure 1.

40 All these figures are with enlarged scale.

The stem or pin 1 bears, on its circumference, two holes or pockets 2-3, suitably distant from the point, and lying at both ends of a diameter as shown by Fig. 2. The edges 45 of both said holes are rounded, in order to avoid any sharp edges. The lengthwise profile of holes 2-3 is a sloping one, and gradually joins the cylindrical surface of the pin. Said pin is fastened by means of a metallic 50 strap 4, which is elastic to a certain extent, and whose both legs have jaw-shaped ends 5-6.

Strap 4 is contained in a case or box 7, shaped either as a cylinder, or as a prism, 55 with one tapered end. Said strap 4 is held

within said box 7 by any suitable way, for instance by means of a stud 8 on its base, retaining a small helical spring against a small shoulder 10, and also by means of two lateral feathers 11-12, fastened on box 7, 60 corresponding with two notches 13-14, on the strap. Said notches are something wider than the feathers, thus providing for the required amount of clearance.

For allowing the introduction of strap 4 65 in the box 7, said box may have a removable bottom.

The outside surfaces of the jaws 15-16 are oblique shaped; the inside surfaces of said jaws are curved, according to the round 70 or oval shape of holes 2-3 on the pin.

Both parts 1 and 7 being separated, assume the user of such a device wants to put and fasten the pin 1 into case 7, it may be easily done by putting pin 1 into hole 17 and 75 forcing said pin through the jaws of strap 4, but the pull exerted upon the pin will push back the said strap, until the resistance of the spring 9 stops the motion.

Assumed that pin 1 be pulled or drawn 80 the opposite way, strap 4 will follow said pin, and the jaws 5-6 will act as wedges, in combination with the inside walls of the tapered end of case 7; said wedge action is so much stronger that the pull itself on the pin 85 1 is a more energetic one. Things are precisely going on by this way in case of any accidental pull. By average conditions of strengths of the pull, the pin is locked, and prevented from slipping away. 90

Usually, if required, the pin will be removed by revolving said pin a quarter of a turn. By this operation, surfaces 18-19 (viz Fig. 2), acting like cams, will open the jaws 5-6, and then the pin 1 may be freely 95 removed.

It will be understood that the constructive detail features may change in a very large extent, though allowing the same result.

Strap 4 may have merely one jaw, provided that the pin 1 can be pressed strong enough by the end of said jaw, when it comes into the hole of the stem, and provided that there be a sufficient resistance on the opposite side of the stem. 100

The end of the pin, which enters between the jaws of strap 4, may be corrugated, instead of having holes like 2-3. In this case, the corrugations will act the same way as the holes 2-3. 110

The system above described is able to be used for many various appliances, namely as a point-cover or protector for hat-pins.

What I regard as new and desire to secure by Letters Patent is:

1. A pin having a pocket, a yieldable catch normally urged into said pocket and adapted to be disengaged from the pocket upon a rotary movement of the pin, and a case for the catch adapted to guide the catch into the pocket upon a longitudinal movement of the pin and catch in the direction to remove the pin from the case.
2. A device of the character described comprising a pin having a pair of pockets at diametrically opposite points with walls rounded longitudinal and circumferential, the portions of the pin between the openings being left blank, a strap of resilient material having jaws at its free ends adapted to yieldably engage in said pockets and guided by the curved walls of the pockets out of engagement therewith when the pin is

turned, and a case receiving the strap and acting to force the jaws more firmly into the pockets on withdrawing movement of the pin.

3. In combination with a pin having a lateral pocket, a yieldable catch normally urged in the pocket and adapted upon a rotary movement of the pin to be disengaged from said pocket, a case to receive the pin and to hold the catch, said case and catch having mutually tapered walls adapted to guide the catch into the pocket automatically upon an axial movement of the pin in a direction to withdraw the pin from the case, and yieldable means for independently urging the catch against the tapered wall of the case.

In testimony whereof I affix my signature in presence of two witnesses.

GUSTAVE ANTOINE RENAULT.
